UNITED STATES PATENT OFFICE

91,913

DESIGN FOR A SERVICE STATION

Frederick C. Van Dusen, Philadelphia, Pa., assignor to The Atlantic Refining Company, Philadelphia, Pa., a corporation of Pennsylvania

Application February 6, 1934, Serial No. 50,648

Term of patent 14 years

To all whom it may concern:

Be it known that I, FREDERICK C. VAN DUSEN, a citizen of the United States, residing at Philadelphia, in the county of Philadelphia, and State of Pennsylvania, have invented a new, original, and ornamental Design for a Service Station, of which the following is a specification, reference being had to the accompanying drawing, forming a part thereof.

Fig. 1 is a front perspective view of a service station embodying my new design.

Fig. 2 is a perspective view of the same showing the front and one side.

Fig. 3 is a perspective view of the same showing the rear and one side.

Fig. 4 is a plan outline of the service station made on a reduced scale.

I claim:

The ornamental design for a service station, substantially as shown.

F. C. VAN DUSEN.
